UNITED STATES PATENT OFFICE.

JOHN HAGEN, OF ST. LOUIS, MISSOURI, ASSIGNOR TO UNION SPECIAL MACHINE COMPANY, OF CHICAGO, ILLINOIS, A CORPORATION OF ILLINOIS.

ADJUSTABLE GUIDE FOR STAYING MACHINES.

Application filed October 4, 1919. Serial No. 328,436.

To all whom it may concern:

Be it known that I, JOHN HAGEN, a citizen of the United States, residing at St. Louis, in the city of St. Louis, State of Missouri, have invented certain new and useful Improvements in Adjustable Guides for Staying Machines, of which the following is a description, reference being had to the accompanying drawing and to the figures of reference marked thereon.

The invention relates to new and useful improvements in tape guides, and more particularly to tape guides which are associated with an attachment for cutting and directing a stay strip to a stitching mechanism.

It has been a common expedient in the sewing machine art to feed by means of a manually controlled feed finger, a stay strip to the stitching mechanism and to cut said stay strip by said manually controlled means. The cutting is brought about by a reciprocating cutter which moves across the path of the stay strip and severs the same. Considerable difficulty has been experienced in properly guiding the end of the stay strip after it has been cut, to the presser foot for the next staying operation.

An object of the present invention is to provide guiding devices for the stay strip which are located between the cutting mechanism and the needles of the stitching mechanism, so as to control the stay strip until it is received under the presser foot and also to guide said stay strip during the stitching thereof.

A further object of the invention is to provide guides of the above character, which guides are adjustable and which are readily accessible for adjustment, and which are also visible to the operator, so that it may be easily seen whether the stay strip is being properly directed to the stitching mechanism.

These and other objects will in part be obvious and will in part be hereinafter more fully disclosed.

In the drawings which show by way of illustration one embodiment of the invention—

Figure 1 is a plan view of a part of a sewing machine having my improved guiding devices applied thereto;

Figure 2 is a front view of the same.

In the patent granted to Benjamin V. Kershner January 18, 1916, No. 1,169,088, there is shown and described a stay cutting attachment for sewing machines, wherein the stay strip is fed forward beneath the presser foot by a manually controlled finger. The means which controls this feeding finger also operates a cutter. When the lever is depressed which controls the finger and cutter, the cutter is raised to sever the stay strip. When the lever is raised then the feed finger moves the tape forward to the front end of the presser foot and into engagement with the feed. My invention is adapted to be used in connection with an attachment of the character described in said patent.

The improved means for the stay strip devised by me consists of guiding devices located between the cutter and the stitching mechanism, which guiding devices are open to view by the operator, so that it can be readily determined whether the stay strip is being properly guided. These guiding devices also insure that the stay strip when fed forward by the feeding finger shall be guided so that the stay strip will be properly centered relative to the needles. Said guiding devices are also adjustable, so as to shift the position of the stay strip or accommodate stay strips of different widths and also center the strips.

Referring more in detail to the drawings, I have shown my improved guiding device applied to a stay cutting attachment which includes a reciprocating cutting blade 1, cooperating with a stationary cutting blade 2. The attachment is mounted on the work support of the sewing machine, which is indicated at 3 in the drawings. The feeding mechanism includes a feed dog which is indicated at 4 in the drawings and a stitching mechanism having two needles indicated at 5 and 6, respectively, in the drawings. The stay strip is fed forward by a feeding finger which is mounted on an arm 7 carried by a shaft 8. Said arm is oscillated by means of a lever 9 which is manually controlled by a spring 10 which moves the lever when released by the operator. The cutter is controlled by this lever 9. These parts of the stay cutting attachment are all similar to those shown and described in the Kershner patent, and have only been illustrated more or less

diagrammatically in the present drawings in order to show the relative position and operation of my improved guiding devices.

My improved guiding devices consist of two edge guiding members 11 and 12. The member 11 is carried by an arm 13 which rests on the upper face of the work support. The cover plate 30 of the staying attachment proper is formed with a recess 14 and said arm 13 has a projecting member 15 which lies in said recess. Said projecting member is formed with an open ended slot 16 and a set screw 17 passing through the slot adjustably secures said arm 13 in position. By loosening the screw the arm 13 may be moved so as to adjust the edge guide 11 in a direction at right angles to the line of feed or the path of travel of the stay strip. The edge guide 12 is carried by an arm 18 which also has a projecting member 19 extending into a recess 20 in the cover plate of the stay cutting attachment and said projecting member is formed with an open ended slot 21 similar to the slot 16, in which is placed a screw 22. By loosening this screw the edge guide 12 may be adjusted in a direction at right angles to the line of feed or the path of travel of the stay strip. The stay strip is indicated at S in the drawings. Said stay strip passes through the cutting attachment across the path of movement of the cutting blade 1, which is manually controlled by the lever 9. When said cutting blade is raised the stay strip will be severed. This is accomplished by depressing the lever 9. When the lever 9 is raised through the action of the spring 10, the feed finger moves the stay strip forwardly to a point close to the needles 5 and 6. The edge guides 11 and 12 are located between the reciprocating cutting blade 1 for severing the stay strip and the needles 5 and 6, so that when this cut edge is projected forwardly by the feeding finger, these edge guides will control and direct the stay strip until it reaches a point underneath the presser foot of the sewing machine. Furthermore, the edge guides will control the stay strip at all times as it passes from the cutting attachment to the needles. These edge guides are visible to the operator, so that it may be readily seen whether the

stay strip is running properly to the stitching mechanism. Said edge guides are also capable of being independently adjustable in a direction at right angles to the line of feed, so that the said strip may be shifted laterally to properly position the same relative to the needles or the edge guides may be adjusted toward and from each other to accommodate different widths of stay strips.

While I have described the invention as particularly adapted for a stay strip passing through a stay cutting attachment, it will be obvious that from certain aspects of the invention, it may be used for other purposes in connection with the guiding of tapes or the like.

Having thus described my invention, what I claim as new and desire to secure by Letters Patent, is:

1. The combination of stitching mechanism including needles, a stay cutting attachment including a movable cutting blade, and guiding means for a stay strip including edge guides located between the needles and the cutting blade, and means for supporting said edge guides upon said attachment whereby they may be independently adjusted at right angles to the path of movement of the stay strip in the direction of the plane of the stay strip.

2. The combination of stitching mechanism including needles, a stay cutting attachment including a cutting blade and a cover plate, means for guiding a stay strip including edge guides located between the cutting blade and the needles, supporting arms for said edge guides, projecting members carried by said arms and having slots formed therein, said cover plate for the stay cutting attachment having recesses formed therein adapted to receive respectively the projecting members carried by said arms, and screws for securing said projecting members to the cover plate, said slots and cover plate recesses being so disposed that the edge guides may be adjusted in a direction at right angles to the path of travel of the stay strip in the plane of the stay strip.

In testimony whereof, I have affixed my signature.

JOHN HAGEN.
